(57) **CLAIM**

The ornamental design for a memory heat dissipation sink as shown and described.

DESCRIPTION

FIG. 1 is a perspective view of a memory heat dissipation sink showing my new design;

FIG. 2 is a front view thereof;

FIG. 3 is a rear view thereof;

FIG. 4 is a left side view thereof;

FIG. 5 is a right side view thereof;

FIG. 6 is a top view thereof;

FIG. 7 is a bottom view thereof;

FIG. 8 is a cross-sectional view taken in the direction of line 8-8 of FIG. 2;

FIG. 9 is a cross-sectional view taken in the direction of line 9-9 of FIG. 2;

FIG. 10 is a portion of the front view of FIG. 2 enlarged for magnification purposes;

FIG. 11 is another portion of the front view of FIG. 2 enlarged for magnification purposes;

FIG. 12 is an enlarged view of FIG. 4;

FIG. 13 is an enlarged view of FIG. 5;

FIG. 14 is a portion of the top view of FIG. 6 enlarged for magnification purposes;

FIG. 15 is another portion of the top view of FIG. 6 enlarged for magnification purposes;

FIG. 16 is a portion of the bottom view of FIG. 7 enlarged for magnification purposes; and,

FIG. 17 is another portion of the bottom view of FIG. 7 enlarged for magnification purposes.
